US0D1037101S

(12) **United States Design Patent** (10) **Patent No.:** **US D1,037,101 S**
(45) **Date of Patent:** **** Jul. 30, 2024**

(54) **USER INTERFACE**

(71) Applicant: **Globe (Jiangsu) Co. Ltd.**, Changzhou (CN)

(72) Inventors: **Christopher Eichel**, Charlotte, NC (US); **Paulius Bulovas**, Malmo (SE); **Jaquline Hultman**, Malmo (SE)

(73) Assignee: **Globe (Jiangsu) Co. Ltd.**, Changzhou (CN)

(**) Term: **15 Years**

(21) Appl. No.: **29/852,277**

(22) Filed: **Sep. 6, 2022**

(51) **LOC (14) Cl.** **12-16**

(52) **U.S. Cl.**

USPC **D12/192**

CLAIM

The ornamental design for a user interface, as shown and described.

DESCRIPTION

FIG. 1 is a perspective view of a user interface, according to the present invention;

FIG. 2 is a left side elevational view of the user interface of FIG. 1;

FIG. 3 is a right side elevational view of the user interface of FIG. 1;

FIG. 4 is a front elevational view of the user interface of FIG. 1; and,

FIG. 5 is a top plan view of the user interface of FIG. 1. The dashed lines in the Figures are for environmental purposes only and do not form a part of the claimed design.

1 Claim, 5 Drawing Sheets
